UNITED STATES PATENT OFFICE

155,089

DESIGN FOR A MIXER

Clarence Karstadt, Glen Ellyn, Ill., assignor to
Birtman Electric Company, a corporation of
Illinois

Application February 26, 1948, Serial No. 144,749

Term of patent 14 years

(Cl. D44—1)

To all whom it may concern:

Be it known that I, Clarence Karstadt, a citizen of the United States, residing at Glen Ellyn, in the county of Du Page and State of Illinois, have invented a new, original, and ornamental Design for a Mixer, of which the following is a specification, reference being had to the accompanying drawings, forming a part thereof, in which:

Fig. 1 is a side elevational view of a mixer showing my new design;

Fig. 2 is a side elevational view thereof taken at substantially right angles to Fig. 1; and

Fig. 3 is a plan view thereof.

I claim:

The ornamental design for a mixer, as shown.
CLARENCE KARSTADT.
